DESCRIPTION

FIG. 1 is a top front perspective view of a conveyor belt cleaning apparatus scraper illustrating the design of the present invention;

FIG. 2 is a bottom front perspective view of the conveyor belt cleaning apparatus scraper of FIG. 1;

FIG. 3 is a left side view of the conveyor belt cleaning apparatus scraper of FIG. 1;

FIG. 4 is a right side view of the conveyor belt cleaning apparatus scraper of FIG. 1;

FIG. 5 is a front view of the conveyor belt cleaning apparatus scraper of FIG. 1;

FIG. 6 is a rear view of the conveyor belt cleaning apparatus scraper of FIG. 1;

FIG. 7 is a bottom view of the conveyor belt cleaning apparatus scraper of FIG. 1; and,

FIG. 8 is a top view of the conveyor belt cleaning apparatus scraper of FIG. 1.
